MAX C. SCHRANK, OF BRIDGETON, NEW JERSEY

SLIP

Application filed January 29, 1931. Serial No. 512,042.

My invention relates to the manufacture of underslips for women and girls and particularly to the manufacture of the type of slip which is slit or open lengthwise to permit freedom of motion for the legs and the skirt or lower portion of which is made with two plies of fabric to permit the use of a thin or light fabric without unduly revealing the legs of the wearer.

10 The object of my invention is to provide for the manufacture of slips having the above features and advantages in any size and conforming to any figure, with the use of a minimum of material and labor and at 15 a minimum cost.

To this end my invention, in its entirety and present specific embodiment, consists of a slip made of a medial waist and skirt piece for the front, a medial waist and skirt piece 20 for the back, an extra ply doubling the medial front skirt portion, an extra ply doubling the medial back skirt portion, one of said doubled skirt portions being open at the sides, and sizing and shaping pieces stitched 25 on opposite sides to the respective medial back and front waist and skirt portions, substantially as hereafter more fully described.

In order that my invention may be fully understood I shall first describe more in detail the method in which I at first prefer to carry the invention into practice and then point out its novel features in the claim.

Reference is to be had to the accompanying drawings forming part of this application in which the same parts are designated by like numbers in both figures. Figure 1 is a front view of a slip made in accordance with my invention, in use.

Figure 2 is an enlarged rear view of the side slip.

The specific embodiment of my improved slip thus illustrated, is made of a medial front combined waist and skirt piece 3 and a medial back combined waist and skirt piece 4, each of said medial pieces being preferably made in one piece, and each of a uniform breadth and shape for all sizes and shapes of the slip and wearer. Said medial and front portions could, however, be made 50 each in two or more pieces if desired.

To the opposite sides of said medial front and back pieces respectively are stitched the corresponding side edges 7, 8, 9, and 10 of opposite side sizing and shaping pieces 5 and 6, which are varied in width and contour 55 according to the size and shape of the slip to fit figures of various sizes and shapes.

The slips can thus be made to fit all sizes and shapes of figures by varying the size and contour of these side pieces 5 and 6, 60 without altering the dimensions or shape of the medial pieces 3 or 4.

To permit the use of thin material without clearly revealing the legs or upper leg region of the wearer, I stitch preferably to 65 and under the skirt portion of the front medial piece 3, a doubling ply 11 which is stitched along its upper transverse edge 12 below the waistline to the medial portion 3, and along its side edges to the side edges 7 70 and 9 respectively of the side pieces 5 and 6, and the medial piece 3. To the same end I stitch preferably to and under the skirt portion of the back medial piece 4 below the waistline the upper transverse edge 13 of a 75 rear doubling piece 14. Said skirt doubling piece 14 is stitched along its vertical side edge 15 to the side edge 8 of the side piece 5, but is left separate on its opposite side edge 16 from the side edge 10 of the side 80 piece 6 to permit the slip to open vertically there and give full freedom of motion to the legs of the wearer.

For the same reason the side edge 17 of the rear skirt portion 4 over the doubling 85 piece 14 is left separate from the corresponding side edge 8 of the side piece 5.

It is evident that the doubling pieces 11 and 14 could if preferred, be attached to the outside of the skirt portions of the front 90 and back medial pieces 3 and 4, but I prefer, as stated, to place them on the inside of said medial pieces, to conceal the transverse seams 12 and 13. As the material of the slip is doubled for invisibility only at its medial lower or skirt portion, and only a single thickness of material is used for the side pieces, a great saving of material is effected. As only the side pieces 5 and 6 have to be varied to make slips of various 100

sizes and shapes, a further great saving of time and labor is accomplished.

It is evident that many changes may be made in the details of design and manufacture without departing from the boundaries of my invention, which is defined by the following claim.

An additional advantage of my invention is that wearers preferring the slip without 10 the side slit or opening can close it themselves by stitching, without making the garment too confining to the limbs, owing to the ample fullness given it without waste of material by means of the side sizing and 15 shaping pieces 5 and 6.

I claim as my invention:

A slip made of medial front and back pieces each consisting of a single straight piece of material forming a combined waist 20 and skirt portion, side shaping and sizing pieces each consisting of a single shaped piece of material forming a combined waist and skirt portion, the front combination piece being stitched to the respective side 25 combination pieces along its side edges, and the back combination piece being stitched to the side piece on one side along its entire side edge and on the opposite side along the side edge of the upper portion only, a front 30 skirt doubling ply stitched along its upper and both side edges to the upper and both side edges of the front skirt portion, and a rear skirt doubling ply stitched along its upper edge to the back skirt portion, and 35 along one side edge only to the side edge of the side piece on the side on which the back skirt portion is left separate from the side skirt portion.

MAX C. SCHRANK.
